US0D1070977S

(12) **United States Design Patent** (10) Patent No.: **US D1,070,977 S**
(45) Date of Patent: ** Apr. 15, 2025

(54) **PRINTER**

(71) Applicant: **BROTHER INDUSTRIES, LTD.**,
Nagoya (JP)

(72) Inventors: **Hiromitsu Tanaka**, Nagoya (JP);
Hirohide Nawata, Nagoya (JP);
Yukihiko Sato, Nagoya (JP); **Takaaki Oguchi**, Nagoya (JP); **Daiki Okamoto**, Nagoya (JP)

(73) Assignee: **BROTHER INDUSTRIES, LTD.**,
Nagoya (JP)

(**) Term: **15 Years**

(21) Appl. No.: **29/918,697**

(22) Filed: **Nov. 29, 2023**

(30) **Foreign Application Priority Data**

May 30, 2023 (JP) ..... 2023-010895 D
(51) LOC (15) Cl. **14-02**
(52) U.S. Cl.
USPC **D18/50**

(57) **CLAIM**

The ornamental design for a printer as shown and described.

DESCRIPTION

FIG. 1 is a perspective view of the printer;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict parts of the printer that form no part of the claimed design.

1 Claim, 7 Drawing Sheets
